Primary Examiner — Katie Jane Stofko*Assistant Examiner* — Kimberly Barnes(74) *Attorney, Agent, or Firm* — Martin & Ferraro, LLP(57) **CLAIM**

The ornamental design for a tile, as shown and described.

DESCRIPTION

FIG. 1 is a top perspective view of the tile showing our new design;

FIG. 2 is a bottom perspective view of the tile;

FIG. 3 is a top plan view of the tile;

FIG. 4 is a bottom plan view of the tile;

FIG. 5 is a side elevational view of the tile, it being understood that the opposite side elevational view is identical; and

FIG. 6 is a cross-sectional view of the tile taken along line 6-6 in FIG. 5; and,

FIG. 7 is another side elevational view of the tile, it being understood that the opposite side elevational view is identical.

1 Claim, 6 Drawing Sheets(56)
